(57) **CLAIM**

The ornamental design for a adjustable stand for portable electronic device, as shown and described.

DESCRIPTION

FIG. 1 is a front, right perspective view of the adjustable stand for portable electronic device illustrating the new design and showing the device in an open or expanded configuration;

FIG. 2 is a front elevational view of the adjustable stand for portable electronic device illustrated in FIG. 1;

FIG. 3 is a rear elevational view of the adjustable stand for portable electronic device shown in FIG. 1;

FIG. 4 is an left-side elevational view of the adjustable stand for portable electronic device shown in FIG. 1 (the right-side elevational view of the device is a mirror image of FIG. 4); FIG. 5 is a top view of the adjustable stand for portable electronic device shown in FIG. 1;

FIG. 6 is a bottom view of the adjustable stand for portable electronic device shown in FIG. 1;

FIG. 7 is a front, right perspective view of the adjustable stand for portable electronic device shown in FIG. 1 and showing the device in a closed or collapsed configuration;

FIG. 8 is a front elevational view of the adjustable stand for portable electronic device shown in FIG. 7;

FIG. 9 is a left side elevational view of the adjustable stand for portable electronic device shown in FIG. 7 (the right side elevational view of the device is a mirror image of FIG. 9);

FIG. 10 is a front, right perspective view of a second embodiment of the adjustable stand for portable electronic device and showing the device in a open or expanded configuration;

FIG. 11 is a front elevational view of the adjustable stand for portable electronic device shown in FIG. 10;

FIG. 12 is a rear elevational view of the adjustable stand for portable electronic device shown in FIG. 10;

FIG. 13 is a right side view of the adjustable stand for portable electronic device shown in FIG. 10 (the left side elevational view of the device is a mirror image of FIG. 13);

FIG. 14 is a top view of the adjustable stand for portable electronic device shown in FIG. 10;

FIG. 15 is a bottom view of the adjustable stand for portable electronic device shown in FIG. 10;

FIG. 16 is a front, right perspective view of the adjustable stand for portable electronic device shown in FIG. 10 and showing the device in a closed or collapsed configuration;

FIG. 17 is a front elevational view of the adjustable stand for portable electronic device shown in FIG. 16; and,

FIG. 18 is a right side elevational view of the adjustable stand for portable electronic device shown in FIG. 16 (the left side elevational view of the device is a mirror image of FIG. 18).
